UNITED STATES PATENT OFFICE.

EDGAR M. CLARK, OF ALTON, ILLINOIS.

METHOD OF DISTILLING PETROLEUM.

1,119,496.

Specification of Letters Patent.

Patented Dec. 1, 1914.

Application filed April 20, 1914. Serial No. 833,243.

To all whom it may concern:

Be it known that I, EDGAR M. CLARK, a citizen of the United States, residing at Alton, in the county of Madison and State 5 of Illinois, have invented a new and useful Improvement in Methods of Distilling Petroleum, of which the following is a specification.

My invention relates to an improvement 10 in distilling petroleum, particularly for obtaining therefrom low-boiling-point hydrocarbons.

Where in distilling petroleum, according 15 to common practice, the liquid material is contained in a reservoir-like still, to the bottom of which the heat is applied, the danger is ever present of an opening forming in the boiler-bottom, due to flaw in the metal, the bottom burning out, or other 20 cause. When this occurs, the entire contents of the still discharge into the fire, producing a more or less disastrous conflagration. This result is more likely to ensue where the distillation is carried on at a temperature 25 sufficiently high to crack the petroleum-contents of the still, whereby free carbon is developed and accumulates on the still-bottom, on which it lies in red-hot condition and tends to burn it out.

30 The primary object of my invention is to provide a method of distilling petroleum, whereby discharge of the contents of the still, through an accidental opening occurring therein from any cause, shall not produce serious consequences but shall avoid damage of any kind other than the loss of a small part of the charge and temporary disabling of the still.

The accompanying drawing illustrates 40 diagrammatically, as suitable for the practice of my improved method, an equipment of apparatus involving a so-called pressure-still, in which the distillation is carried on under high temperature (of 650° to 850° F.) 45 and a pressure of 3 to 7 atmospheres produced by the vapors discharging from the still.

At 1 is shown an upright tank or reservoir supported in elevated position and 50 having a rounded bottom, from above which leads a pipe 2 containing a force-pump 3, of any suitable construction. This pipe leads from the discharge-side of the pump to one end of a pipe-coil 4 in a furnace 5, 55 which is preferably coal-burning. The opposite end of the coil communicates

through a pipe 6 with the reservoir 1 at its upper end, from which leads a discharge-pipe 7 to the upper end of a water-cooled condenser-coil 8, the discharge-end of 60 which, containing a valve 9, leads to a receiving-drum 10 for the distillate. A pipe 11 rises from the lowermost branch of the coil 8 through the condenser-tank, above which the pipe contains a valve 12.

65 The apparatus shown is particularly designed for the manufacture of gasolene by distilling under pressure the residue of petroleum-distillation, such as fuel-oil, to produce it. It is to be understood, however, 70 that my invention is applicable generally to the distillation of petroleum while it has peculiar advantages in connection with the pressure-distillation process referred to. In the apparatus illustrated, the liquid material to be distilled is charged into the reservoir, which may contain several thousand 75 gallons. With the pump in action and the furnace going, the valves 9 and 12 being closed, the contents of the reservoir are circulated, passing from the reservoir by way of the pipe 2 through the pump, which forces the liquid in a relatively-fine stream through the coil 4, whence it returns in heated condition through the pipe 6 to the reservoir. By continuing this circulation, the heated liquid returning from the coil 4 to the reservoir heats the contents of the latter and the resultant vapors pass off through the upwardly-inclining pipe 7 and condenser. These vapors build up a pressure 80 on the contents of the reservoir of from about 3 to 7 atmospheres and raise their temperature to about 650° F. and as the run proceeds, to about 850° F. Gases accumulating in the condenser are allowed to escape from time to time, on opening the valve 12, for relieving the gas-pressure, which is liable to accumulate in the coil and obstruct the action of the apparatus. 85 From time to time the valve 9 is opened for discharging the distillate into the drum 10. This distillate is crude gasolene of superior quality, and it may be subjected to further treatment, well-known in the art, for refining it.

90 By thus subjecting to the action of heat the material under treatment in a relatively fine stream, while free carbon is formed in the liquid passing through the coil 4, it 100 courses under the high pressure at which the liquid is circulated so rapidly through

the same as to prevent accumulation therein of the carbon, which it carries back into the reservoir in the bottom of which it may accumulate without injurious effect, since 5 there is no fire under the reservoir. Should, however, a leak accidentally occur in the coil, so little of the liquid will discharge into the fire in the furnace that no damage will ensue. My improved method, therefore, not only greatly decreases the danger of accident, but if the latter occurs the resultant damage is comparatively immaterial. Moreover, it enables from 10 to 7 runs to be made of the still without requiring 15 the apparatus to be stripped and cleaned, whereas where the boiler 1 is fired but one run can be made without stripping and cleaning the carbon deposit out of it.

While a pump is shown for circulating 20 the liquid material, any other way of producing the necessary rapid circulation is intended to be within my invention.

What I claim as new and desire to secure 25 by Letters Patent is:—

1. The method of distilling petroleum, which consists in circulating it forcibly and rapidly in a relatively-small stream under confinement and subjection to a cracking temperature from and back to a bulk-supply of the liquid material, taking off and 30

condensing the resultant vapors and maintaining a pressure of said vapors on said supply.

2. The method of distilling liquid residue of petroleum-distillation, which consists in 35 circulating said liquid forcibly and rapidly in a relatively-small stream under confinement and subjection to heat from and back to a bulk-supply of the residue, taking off and condensing the resultant vapors and 40 maintaining said liquid at a temperature of from about 650° F. to about 850° F. under a pressure thereon of said vapors of about 3 to 7 atmospheres.

3. The method of distilling liquid residue 45 of petroleum-distillation, which consists in circulating said liquid forcibly and rapidly in a relatively-small stream under confinement and subjection to heat from and back to a bulk-supply of the residue, taking off and condensing the resultant vapors and 50 maintaining said liquid at a temperature of from about 650° F. to about 850° F. under a pressure thereon of said vapors of about 3 to 7 atmospheres exerted throughout their course to and during condensation.

EDGAR M. CLARK.

In presence of—

NELLIE B. DEARBORN,
DAISY C. THORSEN.

Correction in Letters Patent No. 1,119,496.

It is hereby certified that Letters Patent No. 1,119,496, granted December 1, 1914, upon the application of Edgar M. Clark, of Alton, Illinois, for an improvement in "Methods of Distilling Petroleum," was erroneously issued to the inventor, said Clark, whereas said Letters Patent should have issued to *Standard Oil Company, of Whiting, Indiana, a corporation of Indiana*, as assignee of the entire interest in said invention, as shown by the records of assignments in this office; and that the said Letters Patent should be read with this correction therein that the same may conform to the record of the case in the Patent Office.

Signed and sealed this 15th day of December, A. D., 1914.

[SEAL.]

J. T. NEWTON,

Acting Commissioner of Patents.
